CLAIM

The ornamental design for a display screen or portion thereof with graphical user interface, as shown and described.

DESCRIPTION

FIG. 1 is a front view of a display screen or portion thereof with graphical user interface showing our new design; FIG. 2 is a front view of a second embodiment thereof; FIG. 3 is a front view of a third embodiment thereof; and, FIG. 4 is a front view of a fourth embodiment thereof. The broken lines illustrating portions of the graphical user interface form no part of the claimed design. The broken lines illustrating the display screen or portion thereof is for environmental purposes only and form no part of the claimed design.

1 Claim, 2 Drawing Sheets
